B. SKIDMORE, JR.
HYDRAULIC AIR COMPRESSOR AND VACUUM PRODUCER,
APPLICATION FILED AUG. 12, 1918.

1,392,855.

Patented Oct. 4, 1921.

Inventor

Benjamin Skidmore, Jr.

By *Benjamin Skidmore, Jr.*

UNITED STATES PATENT OFFICE.

BENJAMIN SKIDMORE, JR., OF CHICAGO, ILLINOIS.

HYDRAULIC AIR-COMPRESSOR AND VACUUM-PRODUCER.

1,392,855.

Specification of Letters Patent.

Patented Oct. 4, 1921.

Application filed August 12, 1918. Serial No. 249,499.

To all whom it may concern:

Be it known that I, BENJAMIN SKIDMORE, Jr., a citizen of the United States, residing at Chicago, in the county of Cook and State 5 of Illinois, have invented certain new and useful Improvements in Hydraulic Air-Compressors and Vacuum-Producers, of which the following is a specification.

This invention relates to improvements in 10 hydraulic air compressor and vacuum producers of the general type disclosed in my application Serial No. 216618, and the present invention has for one of its objects to provide improved means for removing a portion 15 of liquid from a body or supply of liquid, and which means also operates to deliver air or a gaseous fluid into the said body or supply to replace the liquid removed therefrom.

20 A further object is to provide an improved apparatus of this character embodying a vacuum chamber and a compression chamber and means whereby liquid may be readily transferred from one of the chambers 25 into the other chamber for creating a partial vacuum in one of the chambers or a compression in the other chamber by maintaining a substantially constant liquid level in the chambers.

30 To the attainment of these ends and the accomplishment of other new and useful objects as will appear, the invention consists in the features of novelty in substantially the construction, combination and arrangement 35 of the several parts, hereinafter more fully described and claimed and shown in the accompanying drawings illustrating this invention, and in which:

Figure 1 is a view partly in vertical section and partly in elevation of an improved apparatus of the character constructed in accordance with the principles of this invention.

Fig. 2 is a vertical sectional view taken 45 on line 2—2 Fig. 1.

In the drawing, the apparatus is shown as embodying two reservoirs 10 and 11, preferably superposed, and which reservoirs are separated by means of a chamber or casing 50 12 which is preferably hollow, and is provided with an opening 13, forming communication with the reservoir 10, and openings 14—15 forming communication with the reservoir 11, and by means of which openings 55 liquid in the reservoir 10 may be, under certain conditions, transferred from the reser-

voir 10 through the casing 12 and into the reservoir 11, and a gaseous fluid or vapor, may, under certain conditions, be conveyed from the reservoir 11 through the openings 60 14—15 and opening 13 back into the reservoir 10 to replace the liquid removed from the latter.

In order to accomplish this operation there is provided within the casing 12 a reciprocating element 16 of a size in cross section to fill the casing and is of a length to cut off, under predetermined conditions, communication between the opening 13 and the respective openings 14—15. Coöperating 65 with the element 16 and spaced longitudinally therefrom are elements 17—18 preferably in the form of piston heads, all of the elements 16—17—18 being connected with a piston rod 19 slidable in a suitable bearing 20 by means of a crank 21 connected with the piston rod by means of a link 22. This crank 21 is rotated in any suitable manner, preferably from a motor 23, which latter also operates a pump, preferably of a centrifugal type, and which pump is adapted 70 to withdraw the liquid from the reservoir 11 through the opening 25 and transfer the same by means of the pipe 26 back into the reservoir 10. 75

The elements 17—18 are spaced on opposite sides of the element 16 and in such a position with respect thereto that the spaces between the element 16 and the respective elements 17—18 will be alternately moved 80 into and out of communication with the opening 13 in the element 12 so as to receive liquid from the reservoir 10. These elements 16—17—18 are also adapted during 85 their reciprocating movement, to assume positions so that the spaces between the element 16 and the respective elements 17—18 will be alternately moved into and out of communication, respectively, with the openings 14—15. When the elements are in the 90 position shown in Fig. 1, the space between the elements 16 and 18 will be in registration with the opening 13 to receive liquid from the reservoir 10, and the space between the elements 16 and 17 will be in communication 95 with the opening 14 to discharge the liquid previously received in the space, into the reservoir 11. When this space is empty of liquid, air or gaseous fluid in the reservoir 11 will enter the space so that when the elements are moved so as to discharge the 100 supply of liquid which has been trapped in

the space between the elements 16 and 18 through the opening 15 into the reservoir 11, the air or gaseous fluid which has been trapped in the space between the elements 16 and 17 will be discharged into the reservoir 10 when the said space moves into communication with the opening 13.

It will thus be manifest that predetermined quantities of liquid will be intermittently removed from the reservoir 10 and delivered into the reservoir 11, and the gaseous fluid or vapor which is intermittently removed in predetermined quantities, will be delivered into the reservoir 10 through the liquid therein. This operation creates a suction or partial vacuum in the reservoir 11 which will be manifested in a pipe or passage 27, and the gaseous fluid or vapor which is delivered into the reservoir 10 may be discharged therefrom through an outlet pipe 28. A valve 29 may be provided in the pipe 28, which, when closed, will permit the gaseous fluid or vapor to be compressed in the reservoir 10.

25 This operation is produced by means of the fact that the liquid in the reservoir 10 is maintained at a substantially constant level by transferring the liquid from the reservoir 11 back into the reservoir 10.

30 What is claimed as new is:—

1. An apparatus of the character described embodying a reciprocable element, a reservoir for impounding a desired quantity of water at a desired elevation above said element, said element operating to control the discharge of water from the said reservoir, a reservoir for receiving water discharged by the said element, said element also operating to withdraw fluid or vapor from the second recited reservoir and deliver the same into the first recited reservoir, and mechanism for imparting a reciprocating movement to the said element.

2. An apparatus of the character described embodying a reciprocable element, a reservoir for impounding a desired quantity of water at a desired elevation above said element, said element operating to control the discharge of water from the said reservoir, a reservoir for receiving water discharged by the said element, said element also operating to withdraw fluid or vapor from the second recited reservoir and deliver the same into the first recited reservoir, and through the liquid in the latter to be compressed, and mechanism for imparting a reciprocating movement to the said element.

3. An apparatus of the character described embodying a reciprocable element, a reservoir for impounding a desired quantity of water at a desired elevation above said element, said element operating to control the discharge of water from the said reservoir, a reservoir for receiving water discharged by the said element, said element

also operating to withdraw fluid or vapor from the second recited reservoir and deliver the same into the first recited reservoir, mechanism for imparting a reciprocating movement to the said element, and means for maintaining the liquid in the first recited reservoir at a substantially constant level.

4. An apparatus of the character described embodying an element adapted for a forward and backward movement, a reservoir for impounding a desired quantity of water at a desired elevation above said element, said element operating to directly and intermittently discharge predetermined quantities of water from the said reservoir and also operating to intermittently and directly deliver air or a gaseous fluid into the said reservoir to replace the liquid removed therefrom by the said element, mechanism for imparting a forward and backward movement to the said element, and means other than the said element for maintaining the liquid in the said reservoir at a substantially constant level.

5. An apparatus of the character described embodying an element adapted for a forward and backward movement, a reservoir for impounding a desired quantity of liquid at a desired elevation above said element, said element operating to intermittently discharge predetermined quantities of the liquid from the said reservoir, a reservoir for receiving the liquid discharged by said element, said element also operating to intermittently withdraw predetermined quantities of fluid or vapor from the second recited reservoir and deliver the same into the first recited reservoir, and mechanism for imparting a forward and backward movement to the said element.

6. An apparatus of the character described embodying an element adapted for a forward and backward movement, a reservoir for impounding a desired quantity of liquid at a desired elevation above said element, said element operating to intermittently discharge predetermined quantities of the liquid from the said reservoir, a reservoir for receiving the liquid discharged by said element, said element also operating to intermittently withdraw predetermined quantities of the fluid or vapor from the second recited reservoir and deliver the same into the first recited reservoir, and through the liquid in the latter to be compressed, and mechanism for imparting a forward and backward movement to the said element.

7. An apparatus of the character described embodying an element adapted for a forward and backward movement, a reservoir for impounding a desired quantity of liquid at a desired elevation above said element, said element operating to intermittently discharge predetermined quantities of the liquid from the said reservoir, a reservoir

voir for receiving the liquid discharged by said element, said element also operating to intermittently withdraw predetermined quantities of fluid or vapor from the second recited reservoir and deliver the same into the first recited reservoir, mechanism for imparting a forward and backward movement to the said element, and means other than the said element for transferring the liquid from the second recited reservoir into the first said reservoir to maintain the liquid in the latter at a substantially constant level.

8. An apparatus of the character described embodying an element adapted for a forward and backward movement, a reservoir for impounding a desired quantity of liquid at a desired elevation above the element, a housing in which the said element operates, said housing having an opening 20 forming communication with the reservoir and also having a plurality of discharge openings for the liquid, and means for imparting a forward and backward movement to the said element to cause the same to open and close the first recited opening and alternately deliver predetermined quantities of the liquid to the said discharge openings, the said element also operating to alternately receive predetermined quantities of fluid or vapor through the said discharge openings and intermittently deliver the same into the reservoir through the first recited opening in the housing.

9. An apparatus of the character described embodying an element adapted for a forward and backward movement, a reservoir for impounding a desired quantity of liquid at a desired elevation above the element, a housing in which the said element operates, said housing having an opening forming communication with the reservoir and also having a plurality of discharge openings for the liquid, means for imparting a forward and backward movement to

the said element to cause the same to open 45 and close the first recited opening and alternately deliver predetermined quantities of the liquid to the said discharge openings, and a reservoir for receiving the liquid from the said discharge openings, the said element also operating to alternately receive predetermined quantities of fluid or vapor through the said discharge openings and intermittently deliver the same into the first recited reservoir through the first recited 55 opening in the casing.

10. An apparatus of the character described embodying an element adapted for a forward and backward movement, a reservoir for impounding a desired quantity of liquid at a desired elevation above the element, a housing in which the said element operates, said housing having an opening forming communication with the reservoir and also having a plurality of discharge 65 openings for the liquid, means for imparting a forward and backward movement to the said element to cause the same to open and close the first recited opening and alternately deliver predetermined quantities of 70 the liquid to the said discharge openings, a reservoir for receiving the liquid from the said discharge openings, the said element also operating to alternately receive predetermined quantities of fluid or vapor 75 through the said discharge openings and intermittently deliver the same into the first recited reservoir through the first recited opening in the casing, and means for transferring the liquid from the second recited 80 reservoir back into the first recited reservoir to maintain the liquid in the latter at a substantially constant level.

In testimony whereof I have signed my name to this specification on this 8th day of 85 August, A. D. 1918.

BENJAMIN SKIDMORE, JR.
